United States Patent Office.

LUCIEN M. RICE, OF HARTFORD, CONNECTICUT, AND SIDNEY E. ADAMS, OF CHARLESTOWN, MASSACHUSETTS.

Letters Patent No. 90,392, dated May 25, 1869.

IMPROVED APPARATUS FOR TREATING HYDROCARBON-OILS.

The Schedule referred to in these Letters Patent and making part of the same.

To all whom it may concern:

Be it known that we, LUCIEN M. RICE, of Hartford, in the county of Hartford, and State of Connecticut, and SIDNEY E. ADAMS, of Charlestown, in the county of Middlesex, and State of Massachusetts, have invented certain new and useful Improvements in the Mode of Treating Hydrocarbon-Oils; and we do hereby declare that the following is a full, clear, and exact description thereof, whereby a person skilled in the art can make and use the same, reference being had to the accompanying drawings, and to the letters of reference marked thereon.

Like letters in the figures indicate the same parts.

Figure 1 shows a top view of our improved apparatus for treating petroleum and other hydrocarbon-oils.

Figure 2 is a vertical section through the middle of fig. 1.

Our invention consists in aerating and refining the fluid operated upon, by projecting it upward in fine jets, and allowing it to fall, in drops, into a proper receptacle, by means of which the more volatile portion is separated, and passes off into the atmosphere, and a higher "fire-test" is given to the oil.

It also consists in the machinery by which this is effected.

A is a pan, or receptacle for receiving the fluid as it falls.

B is a pipe, leading from the oil-tank, or pump, which enters the side of the pan A, and is turned upward in the middle of the pan, to receive the sprinkler. The oil is forced through this pipe by a force-pump, or by leading the fluid from a higher level.

C is the rose, or sprinkler through which the oil is forced, with sufficient pressure to throw it upward in fine jets, which fall in the form of drops into the pan A.

The aerated oil runs from the pan A, through the pipe D, into a proper receptacle.

The operation of our invention is as follows:

The oil is forced through the pipe B, and is thrown upward from the sprinkler C into the air, in the manner described. The fluid thus projected exposes a large surface to the action of the air, and a great portion of the more volatile part is vaporized, and passes off into the surrounding atmosphere.

The oil falls into the pan A, and flows down to the exit-pipe in a thin layer, whereby its surface is still further exposed to the action of the air. It then passes off through the pipe D.

We do not confine ourselves to the exact form of pan shown in the drawings, but use any receptacle for the oil that presents the required surface to catch it as it falls from the sprinkler.

The advantages of our invention are that a certain degree of "fire-test" can be obtained with a much less percentage of loss than by the usual methods, and that the operation of removing the lighter and more volatile portions of the fluid is more rapidly and economically performed.

Claim.

What we claim as our invention, and desire to secure by Letters Patent, is—

The combination and arrangement of the sprinkler C and its pipe B with the pan A and pipe D, for the purpose of treating and refining hydrocarbon-oils, substantially as herein described.

LUCIEN M. RICE.
SIDNEY E. ADAMS.
